(57) **CLAIM**

We claim the ornamental design for a bird feeder, as shown and described.

DESCRIPTION

FIG. 1 is a top right perspective view of a bird feeder of the present invention;

FIG. 2 is a top left side perspective view of the bird feeder of FIG. 1.

FIG. 3 a right side elevation view of the bird feeder of FIG. 1.

FIG. 4 a right side elevation view of the bird feeder of FIG. 1.

FIG. 5 is a front view of the bird feeder of FIG. 1.

FIG. 6 is a top plan view of the bird feeder of FIG. 1.

FIG. 7 is a bottom plan view of the bird feeder of FIG. 1.

FIG. 8 is a longitudinal cross-sectional view of a bird feeder taken along line 8-8 of FIG. 5.

FIG. 9 is a front, partially exploded view of the bird feeder of FIG. 1; and,

FIG. 10 is top perspective, partially exploded view of the bird feeder of FIG. 1.

1 Claim, 10 Drawing Sheets
